UNITED STATES PATENT OFFICE.

DEAN C. OBER AND ALBERT R. ASKUE, OF EAST CLEVELAND, OHIO.

CUTTER FOR REMOVING CABLE INSULATIONS.

Application filed November 3, 1923. Serial No. 672,683.

To all whom it may concern:

Be it known that we, DEAN C. OBER and ALBERT R. ASKUE, citizens of the United States, residing at East Cleveland, in the county of Cuyahoga and State of Ohio, have invented a certain new and useful Improvement in Cutters for Removing Cable Insulations, of which the following is a full, clear, and exact description, reference being had to the accompanying drawings.

This invention relates to a tool for cutting away the factory applied insulation for high voltage cables to provide a recess to receive a connector such as shown and described in our application filed October 1, 1923, Serial No. 665,794, the object of the invention being to provide an exceedingly simple and highly efficient tool by means of which a smooth tapering recess can be quickly and easily cut and properly centered with reference to the conductor and the metallic outer covering.

Another object of the invention is to provide a cutter for the purpose specified in which the shavings or cuttings will be readily discharged so as not to interfere with the continued cutting operation; and a still further object is to provide a cutter in which the conductor of the cable can be utilized as a centering guide.

Another object is to provide a tool of the kind described comprising two parts, one of which is fitted to the cable and upon which the other part fits, the first part serving as a centering guide for the cutter member.

Another object is to so construct the cutter that the same is drawn inwardly as the cutting operation proceeds.

With these various object in view the invention consists in the novel features of construction and in the manner of combining or arranging the same all of which will be fully described hereinafter and set forth in the appended claims.

In the drawings forming a part of this specification, Fig. 1 is a view illustrating our improved construction of cutter at the initial stage; Fig. 2 is a similar view showing the position the various parts assume at the completion of the cutting operation; Fig. 3 is an end view of the cutter; and Fig. 4 is an enlarged detail sectional view showing a portion of the cutter.

Referring to the drawings 10 indicates the conductor, 11 the factory applied insulation which is usually oil saturated paper

tightly wound about the conductor 10, and 12 is the lead covering applied to the exterior of the factory applied insulation, these three elements constituting the standard type of high voltage cable now employed.

When it is desired to join two sections of this type of cable it is desirable to cut a tapering recess into the factory insulation in order to receive a connector such as shown and described in our application before referred to, and in practice a small portion of the lead covering and factory insulation is removed so as to leave the end of the conductor slightly protruding.

After this is done a guiding sleeve 13 is applied to the end of the cable, said sleeve having an exterior annular shoulder 14 and the end of the sleeve is slightly tapered as shown at 15. The sleeve is also formed with an inwardly projecting shoulder 16 which is intended to abut against the end of the lead covering 12 as most clearly shown and thereby position the sleeve 13 upon the end of the cable.

The cutter comprises the central or core portion 17 and a spiral blade portion 18, the central core portion being formed with the conductor receiving opening or bore 19 extending therethrough.

The extreme forward end of the cutting blade is projected slightly forwardly as indicated at 20 in order to cut into the factory insulation 11, and serve to pull the cutter inwardly, and it will be noted that the inclined faces of the flights 18 are cut away slightly at their inner ends as shown at 21, and that the extreme rear ends which forms the continuous cutting edge are carried slightly rearwardly as indicated at 22 so that spiral shavings will be cut from the factory insulation, and as the tool is fed inwardly by rotation a tapering recess will be cut, and as the cutter feeds inwardly the conductor 10 passes into the central recess or bore 19 of the cutter. In this manner the cutter is guided at the center and a properly centered recess is provided. The rear end of the cutter is substantially cylindrical in shape as shown at 23 and fits snugly into the rear end of a guiding and centering cage 24 and operating handles 25 are passed through oppositely disposed openings produced in the cage and screwed into the cylindrical portion 23 of the cutter thereby effectively connecting the cutter and cage.

and providing the movable portion of the tool.

Openings 26 of considerable area are produced in the forward portion of the cage in order to permit the discharge of the shavings of insulation as they emerge from the cutting blade.

The interior diameter of the forward portion of the cage 24 is substantially equal to 10 the reduced portion of the sleeve 13 and is intended to fit thereon as the tool is moved forwardly or inwardly in order to affect the cutting operation and the tapered end of the sleeve facilitates the fitting of the cage on 15 the sleeve. The shoulder 14 serves as a stop to limit the inward or forward movement of the cutter as it is obvious that when the end of the cage contacts with the shoulder 14 all further progress is arrested, and the 20 continued revolution of the cutter after this stoppage has been effected serves to finish off the walls of the recess, imparting a polish thereto and completely eliminating any rough or protruding edges or portions.

25 As the cage moves along the reduced portion of the guiding sleeve the centering operation is completed inasmuch as we then have the centering effected from both the interior and the exterior, the conductor 10 30 passing into the central bore of the cutting blade providing the interior centering means, and the contact of the cage with the exterior of the guiding sleeve providing the exterior centering means.

35 The forward end of the cutter being shaped as previously described bites into the insulation and feeds the cutter forwardly and owing to the special shape of the spiral flight of the cutter the insulation will be 40 quickly and easily cut off in spiral shavings and discharged at the sides through the openings 26.

When the recess is completed the tool is reversed and the cage slipped from the 45 guiding sleeve and this sleeve is then removed from the end of the cable and the joining or connecting operations can then proceed.

It will therefore be seen that we provide 50 a strong, durable, easily operated and highly efficient form of tool for cutting properly centered tapering recesses in the ends of a high voltage cable having factory wound insulation and a metallic covering.

55 It will also be understood that this tool can be used upon any and all varieties of cables in which insulation of this general type is employed and it will also be under-

stood that slight changes and modifications can be made to suit varying conditions of 60 cable construction without departing from the broad principle of our invention as defined in the claims.

Having thus described our invention, 65 what we claim is:

1. In a device of the kind described the combination with a shouldered guide sleeve adapted to engage the exterior surface of a cable, of a centrally bored spiral cutter and a cage in which said cutter is arranged 70 and provided with rotative means, said cage being adapted to fit upon the guide sleeve thereby to locate said cutter centrally with respect to the exterior surface of said 75 cable.

2. In a device of the kind described the combination with a shouldered cable engaging sleeve adapted to engage the exterior surface of a cable, of a cutter provided with rotative means and with means for engaging the cable engaging sleeve and shoulder thereof thereby to locate said cutter centrally with respect to the exterior surface of said 80 cable.

3. A device of the kind described comprising a sleeve provided with interior and exterior shoulders, said sleeve fitting upon a cable end, and a tapering cutter having a conductor receiving bore, said tapering cutter being arranged in a cage adapted to 90 fit upon the sleeve, and having means for 95 rotating said cage and cutter.

4. A device of the kind described comprising a sleeve provided with interior and exterior shoulders and adapted to fit snugly 95 over a cable with said interior shoulder engaging the end of said cable, a tapering cutter having a central conductor receiving bore, a cage in which the cutter fits and handles connecting the cage and cutter and providing means for rotating said cage and cutter, said cage being adapted to fit upon the end of the sleeve, thereby to locate said cutter centrally with respect to the exterior 100 surface of said cable.

5. In a device of the kind described, a cutter comprising a centrally bored core and a tapered spiral cutting flight, the forward end of said flight being projected forwardly to bite into the material to be cut, and having a continuous cutting edge upon the rear of said flight.

In testimony whereof, we hereunto affix our signatures.

DEAN C. OBER.
ALBERT R. ASKUE.
